UNITED STATES PATENT OFFICE.

GEORGE DUNCANSON, JR., OF JERSEY CITY, NEW JERSEY.

PRINTER'S QUOIN.

Application filed November 28, 1922. Serial No. 603,813.

To all whom it may concern:

Be it known that I, GEORGE DUNCANSON, Jr., a citizen of the United States, and a resident of Jersey City, in the county of 5 Hudson and State of New Jersey, have invented a new and Improved Printer's Quoin, of which the following is a full, clear, and exact description.

The present invention relates to new and 10 useful improvements in printers' furniture, and it pertains more particularly to a printer's quoин.

It is one of the objects of the invention to provide a new and improved printer's 15 quoин in which the elements constituting the quoин after they have been adjusted, may be locked in adjusted position.

With the above and other objects in view, reference is had to the accompanying drawings, in which—

Figure 1 is a detail plan view showing the manner of use of the quoин;

Figure 2 is a detail sectional view taken on the line 2—2 of Fig. 1;

Fig. 3 is a detail sectional view taken on the line 3—3 of Fig. 1;

Fig. 4 is a perspective view of one of the elements of the quoин;

Fig. 5 is a detail perspective view of the 30 other element of the quoин.

Referring more particularly to the drawings, the quoин comprises two members 5 and 6. Each of these members 5 and 6 has an enlarged end portion 7 and 8, respectively, and said enlarged end portions are provided with slots 9 and 10, respectively.

The member 5 of the quoин is provided with a flange or web 11, and said flange or web is slotted as indicated by the reference 40 character 12. The member 6 of the quoин has a flange or web 13, such flange or web 13 being provided with a plurality of guide pins 14 which project therefrom as shown. Each flange of each member is offset with respect to the lateral dimension of its respective member, and each flange when the members are placed together is adapted to be engaged in the slot of the enlarged portion of the opposite flange. By this construction it 50 is apparent that the two members when secured together will form a quoин, the side edges of which will at all times be parallel.

After the members have been placed to-

gether the guide pins 14 are positioned in the flange 13 in such a manner that they project through the slot 12 of the flange 11, and thus form a means for preventing the two members from becoming detached one from the other.

Carried by the enlarged end portion 7 of the member 5, is a set screw 15, and carried by the enlarged end 8 of the member 6, is a set screw 16. The set screw of each member is adapted to engage the flange of the opposite member in such a manner that the two members will be prevented from longitudinal movement relative to each other when the set screws are turned up.

The device operates in the following manner:

The quoин is positioned after it is turned up with a key in the ordinary manner: When this has been accomplished, either of the set screws 15 and 16 may be tightened until it exerts a binding action upon the 75 flange of the member by which it is not carried. Upon turning up the set screw the two members are locked against accidental displacement or longitudinal movement with respect to each other, this insuring 80 proper operation of the quoин.

From the foregoing it is apparent that the present invention provides a new and improved printer's quoин, which after the same has been adjusted, may be locked to 85 retain its adjusted position.

What is claimed is:

A printer's quoин comprising two interengaging wedge-shaped members, each of which is provided with an offset longitudinally-extending flange, an enlarged slotted head portion formed on one end of each of said members, the slotted head portion of each member being adapted to receive the flange of the opposite member, a longitudinal slot formed in the flange of one of the members, guide elements carried by the flange of the other member, said guide elements being adapted for reception within the longitudinal slot of the other member, and means carried in the enlarged head portion of each member and adapted to engage the flange of the opposite member to prevent relative movement of the members, said means comprising set screws.

GEORGE DUNCANSON, Jr.
